UNITED STATES PATENT OFFICE

2,499,498

MOBILE HOUSING UNIT

John Hays Hammond, Jr., Gloucester, Mass.

Application April 29, 1947, Serial No. 744,633

5 Claims. (Cl. 20—1)

1

This invention relates to mobile housing units and more particularly to a housing unit containing complete living quarters, such as a living room, one or two bedrooms, bath and kitchenette, which is transportable from place to place and is adapted to be incorporated as a part of an apartment house, to be placed on a foundation as a detached dwelling, or to be mounted on the hull of a ship.

An object of the invention is to provide a unit of the above type having complete facilities for installation in the supporting structure.

Another object is to provide a unit of the above type which may be installed in a supporting structure, but which may be readily detached and transported to a different locality as desired.

Another object is to provide an apartment house structure including a plurality of removable living units.

Various other objects and advantages will be apparent as the nature of the invention is more fully disclosed.

Although the novel features which are characteristic of this invention are pointed out more particularly in the claims, the nature of the invention will be better understood by referring to the following description taken in connection with the accompanying drawing in which a specific embodiment thereof has been set forth for purposes of illustration.

In the drawing the figure is a perspective view, with parts broken away to show the internal construction, of an apartment house structure incorporating a plurality of living units embodying the present invention.

Referring to the drawing more in detail, an apartment house 11 is shown as provided with steel girders 12 which form essentially a skeleton structure having openings or cells adapted to receive the various housing units 17. The apartment house is provided with a permanent outside wall 13 and on two sides, such as on the front and back, is provided with openings 14 which are normally closed by movable panels 15. The panels 15 are provided with eyes 10 and are adapted to be raised about their upper edges and slid into openings 16 provided between the various sections. The panels 15 may, if desired, be formed in sections and operated in a manner similar to a lift door of standard construction. Suitable rollers (not shown) may be provided to facilitate the operation of the various panels.

The girders 12 form an open framework which is so constructed that a plurality of open cells are provided corresponding in size to the various housing units 17 to be incorporated therein. These cells are formed with inner walls 37 including doors 36 opening on a central hallway 38 and with top and bottom panels which in con-

2

junction with the movable panels 15 close the cells when the housing unit 17 is removed.

Each housing unit 17 forms a complete living unit including the various necessary rooms and facilities which are completely installed. The units are provided with a plurality of rollers 18 which are adapted to slide into horizontal channel members 19 secured to the girders 12 for inserting the units from the front and rear respectively of the house. Vertical channel members 21 are also provided which register with the horizontal channel members 19 and extend vertically past the various tiers of cells. The vertical channel members 21 are provided near their lower ends with outside notches 22 through which the rollers 18 pass and are provided opposite each of the horizontal channel members 19 with registering notches (not shown) to permit the rollers to pass into the horizontal channel members.

Located on the roof of the house 11 are a pair of cranes 24 which are rotatably mounted on a travelling platform 25 provided with wheels 26 travelling on rails 27 secured to the roof and adapted to position the crane over the various tiers of cells. Suitable means may be provided for driving the platform 25 to the selected location. The cranes 24 are shown as rotatable to extend over either the front wall or the back wall of the house for the insertion of the housing units therein. Electrically operated winches 28 are mounted on each crane 24 and carry drums on which are wound steel cables 29 which are of a size to lift the various housing units. The cables 29 pass over pulleys 31 on the cranes 24 and are provided at the lower end with hooks 32 to engage eyes 33 secured to the ends of the housing units 17. Separate winches may be provided for each cable if desired, or a single winch may be provided for actuating all of the cables depending upon the weight of the various units.

The housing units 17 are each provided with suitable outside windows 35 and doors (not shown) which, when the unit is installed, will be adjacent the doors 36 of the apartment house.

The utilities of the housing units 17, such as water, gas, power, etc., are connected by unions 41 and plugs 42 to permanent insulations in the apartment house. Windows 43 are provided in the walls 13 and in the panels 15 of the house and are located to register with the windows 35 of the unit when the latter is in place.

In the operation of this system, the units 17 are installed in a vacant cell in the apartment house by first connecting the hooks 32 to the eyes 18 of the corresponding panel 15, lifting the panel and sliding the same into the opening 16 to leave an outside opening to receive the unit. The unit 17 is then hoisted into place by locating the cranes 24 over the cell space and attaching the hooks 32 of the cables 29 to the eyes 33 of the unit. The

unit is then lifted, the inside roller 18 passed through the notch 22 into the vertical channels 21, and the unit hoisted until it is brought opposite the open cell. The unit is then moved inwardly by suitable means not shown. The rollers 18 pass from the vertical channels 21 into the horizontal channels 19. At suitable intervals during the insertion of the unit, the hooks 32 are released from the eyes 33. When the unit is in place, the utilities are connected to the unions 41 and plugs 42 and the panel 15 is lowered into place over the front of the unit.

When the unit is to be removed, the reverse operation takes place, the panel 15 first being raised, the unions 41 and plugs 42 disconnected, and the unit 17 being slid outwardly in horizontal channels 19. When the unit has been moved sufficiently to expose the eyes 33, the hooks 32 are inserted and a strain is put on the cables 29 to assist in the removal of the unit. The unit is then lowered and may be placed on a suitable trailer truck or other means for transporting the same to a different location. The panel 15 is then lowered into position to close the vacant space.

Each of the units may comprise complete living quarters or a plurality of complementary units may be used which may be located adjacent one another or across the hallway 38 of the building, in which case one unit may include a living room, dining room and kitchenette and the other unit may include bedrooms and bath.

The unit, after being placed on a trailer truck or the like for transportation, may be moved to an apartment structure in another location, or may be placed upon foundations to constitute a detached living unit, or if desired may be attached to a hull and connected to the utilities supply thereof.

Although a specific embodiment has been shown for purpose of illustration, it is to be understood that various changes and modifications may be made therein as will be readily apparent to a person skilled in the art. The invention is only to be restricted in accordance with the scope of the following claims.

What is claimed is:

1. An apartment house structure comprising a framework enclosing a plurality of cells having openings adapted to receive independent living units, permanent hallways carried by said framework, permanent utility connections carried by said framework in positions for connection to the housing unit in each cell, each cell having a movable outer panel adapted to close said opening and a housing unit in one of said cells containing living quarters.

2. An apartment house structure comprising a framework enclosing a plurality of cells arranged in tiers and having openings adapted to receive independent living units, permanent hallways carried by said framework, permanent utility connections carried by said framework in positions for connection to the housing unit in each cell, each cell having a movable outer panel adapted to close said opening, a housing unit in one of said cells containing living quarters, and a travelling hoist mounted on said framework to be positioned over each tier of cells and carrying hoisting cables, said unit having means for the temporary attachment of said cables for hoisting the same into position.

3. An apartment house structure comprising a framework enclosing a plurality of cells ar-

ranged in tiers and having openings adapted to receive individual living units, permanent hallways carried by said framework, permanent utility connections carried by said framework in positions for connection to the housing unit in each cell, each cell having a movable outer panel adapted to close said opening, a housing unit in one of said cells containing living quarters, a travelling hoist mounted on said framework to be positioned over each tier of cells and carrying hoisting cables, said unit having means for the temporary attachment of said cables for hoisting the same into position, a plurality of rollers attached to each unit, vertical channels carried by said framework located at each tier of cells in position to receive said rollers for guiding said units during the hoisting thereof, and horizontal channels carried by said framework registering with said vertical channels and adapted to receive and guide said rollers during the insertion of said units into said cells.

4. An apartment house structure comprising a framework enclosing a plurality of cells arranged in tiers and having openings adapted to receive independent living units, permanent hallways carried by said framework, permanent utility connections carried by said framework in positions for connection to the housing unit in each cell, each cell having a movable outer panel adapted to close said openings, a housing unit in one of said cells containing living quarters, a travelling hoist mounted on said framework to be positioned over each tier of cells and carrying hoisting cables, each unit having means for the temporary attachment of said cables for hoisting the same into position, a plurality of rollers attached to said unit, vertical channels carried by said framework located at said tier of cells to receive said rollers for guiding said units during the hoisting thereof, horizontal channels carried by said framework registering with said vertical channels and adapted to receive and guide said rollers during the insertion of said units into said cells, and means mounting said movable panel for retraction to permit the insertion of said unit into a cell.

5. An apartment house structure comprising a framework carrying walls forming a plurality of cells having openings adapted to receive independent living units, permanent hallways carried by said framework, permanent utility connections carried by said framework in positions for connection to the housing unit in each cell, each cell having a movable outer panel adapted to close said opening, a housing unit in one of said cells containing living quarters, said unit being provided with windows and doors and complementary windows and doors in said walls for registering with said first windows and doors when said unit is in place.
